SEWING MACHINES

Samuel Greisman, London, England, assignor to Comtex Limited, London, England, a British company

Application September 24, 1956, Serial No. 611,432

Claims priority, application Great Britain July 5, 1956

4 Claims. (Cl. 112—11)

This invention concerns improvements in or relating to sewing machines for use in applying a binding over the edge or edges of one or more layer or layers of material and simultaneously sewing such binding and said layer or layers together, and more particularly the invention concerns improvements in or relating to machines for closing or sealing (hereinafter referred to as "sealing"), with the aid of sewing, bags or sacks and the like (e.g. paper, plastic, or fabric envelopes or containers and mattress covers or ticks). More especially the invention concerns machines for use in sealing the mouths of paper and like bags or sacks (hereinafter called "bags") after they have been filled with material, usually pulverulent material such as cement, fertilizers, lime or chemicals used in industry.

There are two principal methods of sealing filled bags by sewing, one comprising passing the filled bags to a sewing machine having a U-shaped gap flanked on opposite sides by the needle operating mechanism and a feed mechanism respectively, the mouths of the bags passing successively through the said gap (usually with the machine so disposed that the said U-shaped gap is in a vertical inverted position) and being sewn up by stitching passing directly through the opposite walls of the bag. The other method referred to is similar to that just mentioned except that the sewing machine is of a portable character and is taken to the bags instead of the latter being taken to the machine. Such a portable sewing machine also has a U-shaped gap as aforesaid and has a handle at its upper part whereby the machine may be suspended over the mouth of the bag and passed laterally across the bag to sew up the mouth thereof.

When a bag has been sewn up by either of the methods referred to there is always a danger that the mouth of the bag will subsequently become torn or even be torn during the sewing operation itself. Moreover, where fine materials are contained in the bag there is always some danger of some leakage of these materials occurring between the stitches used for sealing the bag.

It is an object of this invention to provide, in or for a portable sewing machine for sealing bags, an attachment which enables such a machine to be readily converted from a machine which merely closes bags by sewing into a machine which, in addition, applies a covering strip to the bag seals so as to make the latter tighter and more or less impermeable to the contents of the bag.

It is a further object of this invention to provide, in a portable sewing machine having a covering strip applying attachment according to this invention, a guillotine mounted on the opposite side of the head of the sewing machine to said attachment for severing off that portion of the covering strip which has been applied to a bag.

In order that the invention may more readily be understood and carried into practice, one embodiment of the same will now be described with reference to the accompanying drawings, in which:

Figure 1 is a perspective view of a reel holding and folding attachment constructed in accordance with this invention for attachment to a bag sealing sewing machine;

2

Figure 2 is a front perspective view from one side of a bag sealing sewing machine having the attachment illustrated in Figure 1 and a co-operating guillotine applied thereto;

5 Figure 3 is a front perspective view taken from the other side of the machine shown in Figure 2;

Figure 4 is a fragmentary part-sectional plan of the machine shown in Figures 2 and 3 and illustrates how the attachment shown in Figure 1 can be collapsed into an out-of-the-way position on the said machine; and

10 Figure 5 is a fragmentary section on line V—V of Figure 4.

The drawings illustrate this invention as applied to a bag sealing sewing machine of the known Fischbein type of which an example is described in British Patent No. 648,414. Nevertheless, it should be understood that this invention may be applied to other types of bag sealing sewing machines which may be driven electrically (as the Fischbein machine) either from the electric mains or from a battery, pneumatically or in any other way.

15 Referring to the drawings, 1 is the bag sealing sewing machine which comprises a head 2 having an inverted U-shaped gap 3 and furnished at its upper part with a handle 4 whereby the machine may be suspended over the mouth of a bag such as 5 (Figure 2) passed between the foot 6 of the sewing machine (carried by the forward limb 7 of the head) and the feed mechanism 8 carried by the rear limb 9 of the head of the machine, the arrangement being such that the machine may be suspended over the mouth of the bag 5 and traversed along such mouth to enable the mouth of the bag to be sewn up by means of the needle 10 of the machine, and thread 11 fed from a bobbin 12 carried by the machine, said needle being driven conveniently from an electric motor 13 through a driving shaft 14 and suitable transmission. The foot 6 is withdrawable by means of a lever 15. The sewing machine so far described is of normal known form and no claim is made per se to such a machine.

20 In accordance with this invention, the machine 1 is provided with a tape or covering strip applying attachment. 40 This attachment is mounted on one side of the machine 1, i.e. on the right-hand side viewing the machine from the front, and comprises a reel holder bracket or support generally indicated by the reference 16 and which is shown in Figure 1 detached from the machine. This

25 bracket 16 is conveniently formed from a blank of appropriate sheet metal (e.g. aluminum) pressed to the desired shape and comprises a wall or main panel portion 17 which is furnished at its upper left-hand edge (as the attachment is seen in Figure 2) with a flange or wing 18 which is hinged about a vertical axis 19 to the main panel 17, this wing being furnished with a pair of vertically spaced keyhole slots 20 adapted to receive correspondingly located screws 21 in the right-hand side face of the head 2 of the machine 1 so that the main panel 17 of the reel holder bracket 16 will, when the bracket is fixed to the head of the machine and the main panel 17 is locked at right angles to the wing 18, project laterally from the machine 1 parallel to the line of feed of bags through the gap 3 in the head 2 of the machine.

30 55 60 65 70 75 80 85 90 95 100 As will be clear from Figures 1, 2 and 4 of the drawings, the main panel 17 of the bracket 16 is capable of swinging about the vertical axis 19 relatively to the wing 18 so that the panel 17 may either be arranged in the operative position shown in Figures 1 and 2 and in full lines in Figure 4 or swung rearwardly through 90° into the position indicated in chain-dotted lines in Figure 4 when the main panel 17, and the parts carried thereby and subsequently described, are located in an out-of-the-way position enabling the sewing machine to be used for normal purposes as if the attachment being described was not applied to the machine.

In order to lock the panel 17 in the operative position,

a displaceable strut member 22 hinged at 23 to the lower end of the wing 18 and capable of swinging from an out-of-the-way collapsed position shown in chain dotted lines at 24 in Figure 1 into the horizontal position shown in full lines in Figure 1 behind the panel 17 so as to hold this out from the wing 18 at right angles thereto, the strut 22 having a corner part 25 adapted to engage upon a protuberance 26 extending rearwardly from the panel 17. This panel is prevented from swinging forwardly more than 90° from the wing 18 by means of a vertical stop flange 27 formed integrally with the lower part of the hinged edge of the panel 17 and projecting at right angles forwardly therefrom so that, when the panel 17 is arranged at right angles to the wing 18 and thus perpendicular to the side face of the head 2 of the sewing machine, the stop 27 bears against the side of the rear limb 9 of the head 2 and limits the further forward movement of the panel 17. The front edge of the stop 27 is furnished with a return portion 28 which is adapted to clip the front of the rear limb 9 of the head 1 of the machine as is shown clearly in Figure 4 of the drawings.

In order that the panel 17 may be held in its out-of-the-way position when moved to such position, there is secured to the upper part of the rear side of the panel a suction cup 29 adapted to be adhered to the casing of the electric motor 13.

In an alternative, the panel 17 may be constantly sprung urged to its out-of-the-way position and be held in its operative position, when required, by means of the strut 22.

The panel 17 is furnished with a forwardly projecting spindle 30 fixed at one end, cantilever fashion to the panel. The spindle 30 has a plain portion 31 to receive a reel 32 of covering strip or tape 33 and terminates in a reduced screw threaded portion 34 which receives a cup shaped washer 35 and a clamping nut 36, a spring 37 being provided between the clamping nut 36 and the washer 35 to press the latter into frictional engagement with the reel 32 thereby to hold the latter on the spindle 30 and to prevent the reel 32 overrunning in use. The reel may be formed by winding the covering strip upon a metal, cardboard, wooden or other suitable tubular core which fits freely upon the spindle 30. Alternatively, the strip may be carried by a reel having side flanges between which the strip is located, the reel then being similar to a cinematograph film reel.

From the lower edge of the panel 17 forwardly projects a guide carrying flange 38 having secured on its underside guide means in the form of a covering strip guide 39 having a flattened cross-sectional form at its input end 40 and progressively assuming an even deepening channel section towards its output end 41 (Figure 1). The covering strip 33 is fed from the reel 32 to the guide 39 which progressively converts the strip from its initial substantially flat form into a deep inverted U- or V-form in cross-section.

The guide 39 is conveniently formed from a blank of sheet metal of initially substantially rectangular form having portions 42 of its longitudinal edges 43 doubled over, as shown in Figure 5, upon the blank to form channels into which the edges of the covering strip 33 pass as the strip is fed through the guide 39 and in which the edges of the strip are held until the strip passes from the guide to the head 2 of the sewing machine 1, the said blank being doubled upon itself along its centre line to a progressively increasing extent from its input end 40 to its output end 41 where the blank is most severely bent upon itself. The arrangement being such that the flat strip of covering material is progressively converted from the said flat strip form to the said deep inverted U- or V-shape in cross-section when it is ready to receive between its side flanges the mouth of the bag 5.

At its input end, the guide 39 is rolled upwardly and over upon itself so as to form wide bearing element or a cylindrical transverse portion 44 perpendicular to the

longitudinal edges of the guide and over which the strip passes as it travels from the reel 32 to the guide 39 and by which the strip is smoothed out and slightly tensioned before passing to the guide. In an alternative, the portion 44 may be replaced by a roller to minimise wear and tear on such portion. As shown, the covering strip 33 is conveniently drawn off from the top outer portion of the reel 32 and then fed downwardly and around the cylindrical portion 44, into the guide 39, with the edges of the strip in the laterally spaced side channels of the guide, and forwardly through the guide to the gap 3 in the sewing machine head 2.

So that an operator may keep a very close eye upon the operation of the guide 39, an adjustable mirror 45 is arranged below the level of the guide, this mirror 45 being carried by a screw 46 itself carried by the free end of an arm 47 which is attached at its other end to the cylindrical portion 44 of the guide 39, which for this purpose conveniently extends forwardly beyond the forward longitudinal edge 43 of the guide, by the doubling of the end of the arm 47 over the cylindrical portion 44 and the securing of this doubled over end to an intermediate part of the arm by a thumb screw 48. The mirror 45 is universally adjustable relative to the screw 46, as by being connected thereto through the medium of a ball and socket joint so that the position of the mirror 45 can be set to suit the particular operating position assumed by the operator who can then observe any breakage in the strip 33 or any other untoward happening.

The position of the arm 47 may be adjusted angularly around the axis of the cylindrical portion 44 of the guide 39 by loosening the thumb screw 48 and re-tightening the same when the arm has been moved. By this means the arm 47 may be moved to the position shown in chain dotted lines in Figure 1 to move the mirror 45 to an out-of-the-way position when the panel 17 is to be moved to its out-of-the-way position shown in chain-dotted lines in Figure 4.

The sealing strip will preferably be crepe paper as this is inexpensive, resilient and suitable for the purpose, but other suitable materials may be employed if desired, e.g. stronger materials such as fabric strip.

In the machine being described, there is provided on the side opposite to that on which the covering strip applying attachment is located, i.e. on the left-hand side viewing the machine from the front, a guillotine assembly for severing the covering strip just beyond the trailing end of the sealed mouth of the bag. This assembly comprises a pair of guillotine blades 49, 50 (see Figure 3) pivoted together at one end so as to operate scissor fashion, the blade 49 being secured, e.g. by screwing, to the lower part of the rear limb 9 of the head 2 and at the side of the head so that, as a sealed bag passes entirely from the head of the machine, the other blade 50 can be closed upon the blade 49 to cut off the strip.

The movable blade 50 is furnished with a forwardly extending operating lever 51 having at one end an L-shaped plate 52 by which it is secured to the blade 50 and at the other end a hand knob 53, conveniently formed of rubber or like material, and passing through a guide slot 54 provided in a bracket 55 fitted to the forward limb 7 of the head 2 of the machine. The guide slot 54 limits the extent of movement of the blade 50 and also ensures that the latter will mate satisfactorily with the other blade 49. A spring 56 is secured between the upper edge of the blade 50, and the upper part of the bracket 55 and serves to urge the guillotine blades to their relatively opened positions.

It will be appreciated that the guillotine above described serves not only to cut off the sealing strip but also to sever the cotton used in the sewing operation so that this guillotine will preferably be used whether a sealing strip is being applied to a bag, or not. Moreover, in order to enable the guillotine to be used in sew-

ing up the mouths of jute or similar textile bags where the bag enters the gap in the head of the sewing machine to a greater extent than is usual with the paper bag, the above described guillotine may be modified to make the blades longer, the pivot for the blades being near the top of the gap, the operating arm or lever being curved, the position of the spring modified and the guard suitably correspondingly formed.

I claim:

1. For use with a portable sewing machine having a recessed sewing head with conventional stitching and feed mechanism disposed therein, an auxiliary device for applying and stitching a covering tape over the edge of material to be sewn, said device comprising a support having a wall and a flange extending from a vertical edge thereof, said flange provided with slot means adapted to detachably engage cooperating means disposed on said machine, a spindle carried by said wall adapted to mount a reel of said tape thereon in alignment with said mechanism, adjustable friction means adapted to engage the reel when mounted thereon to oppose free turning of said reel, fold guide means carried by said wall adjacent the lower edge thereof, the input end of said fold guide means being provided with a wide bearing element adapted to spread and smooth said tape, said guide means having a narrow inverted channel output end and adapted to continuously feed

said tape in folded position over the edge of material being fed to said sewing machine for stitching during operation of said mechanism.

5 2. A device according to claim 1 wherein said wall and said flange are connected by a collapsible support means, whereby said spindle-mounted reel and said guide means may be moved from aligned operative position relative to said mechanism to an inoperative position, and means for retaining said device in such inoperative position.

10 3. A device according to claim 2 wherein a displaceable strut disposed on said flange is adapted to engage said wall and maintain said wall in operative position.

15 4. A device according to claim 3 wherein said wall is provided with a clip means adapted to engage said machine and cooperate with said slot means to maintain said device in operative alignment with said mechanism.
